UNITED STATES PATENT OFFICE.

WALTER WRIGHT, OF NEW YORK, N. Y., ASSIGNOR TO UNDERWOOD COMPUTING MACHINE COMPANY, OF NEW YORK, N. Y., A CORPORATION OF NEW YORK.

COMBINED TYPE-WRITING AND COMPUTING MACHINE.

1,283,009.

Specification of Letters Patent.

Patented Oct. 29, 1918.

Original application filed May 12, 1910, Serial No. 560,927. Divided and this application filed October 15, 1917. Serial No. 196,597.

To all whom it may concern:

Be it known that I, WALTER WRIGHT, a citizen of the United States, residing in New York, in the county of New York and State of New York, have invented certain new and useful Improvements in Combined Type-Writing and Computing Machines, of which the following is a specification.

This invention relates to an improvement in combined typewriting and computing machines of the Underwood-Wright type, and is a division of my application, Serial No. 560,927, filed May 12, 1910.

The present case includes certain portions of said parent case which relate more particularly to the accumulating of a series of cross totals in a plurality of individual totalizers. There may also be used one or more main totalizers, and all the totalizers may be connected to move with the traveling typewriter carriage, the main totalizers for a continuous run of the carriage, and the cross-totalizers for intermittent back and forth movements during such continuous run. The main totalizers may be merged into a single long totalizer capable of division or grouping in various ways.

Other features and advantages will hereinafter appear.

30 In the accompanying drawings,

Figure 1 is a front view, in elevation, partly in section and partly broken away, to show the underlying structure.

Fig. 2 is a contracted side view, in elevation, with the cover-plate removed, to show the underlying structure.

Fig. 3 is a diagrammatic view, showing the arrangement for controlling the activity and character of activity of the three totalizers.

Fig. 4 is an enlarged detail view of the gearing between the valuating or indexing mechanism and the master-wheel shafts, whereby connection between the same may be interrupted.

Fig. 5 is a skeleton, perspective view, showing the train of gearing between the typewriter carriage and the track at the front of the machine, for controlling the traveling movements of the traveling elements of the totalizers.

Fig. 6 is a horizontal section, showing the

valuating or indexing mechanism and the setting means for the same.

Fig. 7 is a horizontal section of the parts shown in Fig. 6, taken at a slightly lower plane, and showing one of the setting jacks as partly actuated.

Fig. 8 is a detail view, in end elevation, of the indexing or valuating pin-wheel.

Fig. 9 is a detail view of the slip clutch between the constantly-running motor and the valuating mechanism, whereby, when the latter is locked, the driving connection will be automatically interrupted.

Fig. 10 is a detail view, showing the numeral-key type-action and the means for interrupting the connection between the numeral key and the type, so that computation may be effected.

Fig. 11 is a top plan view of the parts shown in Fig. 10.

Fig. 12 is a detail vertical section taken from left to right, showing the hooks which connect the numeral keys to the types in their operative positions.

Fig. 13 is a view similar to that shown in Fig. 12, except that the hooks have been disconnected from the numeral keys.

Numeral keys 1 operate type-actions in a manner common to the Remington typewriter, to print digits on a work-sheet carried by a platen 2. The platen 2 is mounted to rotate on a carriage 3, which travels on a frame 4. Although the mechanism is shown as applied to a Remington machine, it can just as well be applied to an Underwood machine, or any other similar make. The carriage 3 has the usual step-by-step traveling movements to space between the writing of the digits and other characters. This movement may be controlled by any well-known escapement mechanism.

The numeral keys 1, in addition to typewriting the digits, are arranged to compute them by running the numbers up into totalizers 5, 6 and 7. As will be explained more fully hereinafter, the totalizer 5 is a long totalizer, having a large number of computing wheels 8, which may be separated into groups, to add up vertical columns of numbers, each comprising several digits, as they are typewritten. The short totalizers 6 and 7 are cross-totalizers and

arranged to sum up the horizontal columns of numbers as they are typewritten.

In the present case, mechanism for adding and subtracting is shown. In order that the 5 numeral keys 1 may compute as well as typewrite, when any one of them is depressed, its key-lever 9 draws down on a hook 10 to rock a bell-crank 11, which is connected by a link 12 to actuate a bell- 10 crank 13, arranged to operate a plunger or jack 14. There is one of the plungers or jacks 14 for each of the numerals from "1" to "9", and they are arranged in a circular 15 series, so as to set opposite ones of a series of pins 15 mounted in a pin-wheel 16.

All but one of the pins 15 normally occupy a position projecting from the side of the pin-wheel 16 next to the plungers or jacks 14, and are arranged to be projected individually to the opposite side of the pin-wheel 16, so as to determine the rotation of the pin-wheel 16. This gives an indexing or 20 valuating movement of the pin-wheel 16, which corresponds in its extent to the value 25 of the particular numeral key actuated. The extent of movement is determined by the distance of the pin set from the pin which was previously set and maintained by the wheel 16 in a locked position subsequent to 30 the previous computation. The pins 15 are yieldingly locked in either of their positions by a circular spring 17, which engages alternately in sockets 18, provided in the pins 15.

The pin-wheel 16, when no numeral key is 35 actuated, is locked by a star-wheel 19, engaging the last set pin, indicated specifically at 20, Fig. 8, which determined the extent of the just previous computation. The pin-wheel 16 is normally under a driving tendency 40 to rotate from a motor 21, and will rotate when released by the star-wheel 19. The driving connection includes a slipping mechanism, whereby the motor 21 can continue to rotate when the pin-wheel 16 is 45 locked by the star-wheel 19. This driving connection includes a motor-shaft 22, having a series of spring-clutch-shoes 23 secured thereto, which are arranged to engage in a clutch-cup 24 secured to a shaft 25. The 50 shaft 25 is provided with a beveled gear 26, which meshes with a beveled gear 27 secured to a shaft 28, having a gear 29. The gear 29 drives a gear 30, which, in turn, drives a gear 21 on a shaft 32, to which the pin-wheel 55 16 is secured. Ordinarily, the pin-wheel 16 is held against rotation by the star-wheel 19, so that a slip takes place between the clutch element 23 and the clutch element 24. When, 60 however, the star-wheel 19 is permitted to turn so as to permit a rotation of the pin-wheel 16, the pin-wheel 16 will rotate an amount corresponding to the numeral key just actuated, which rotation will be carried in a manner, presently to be described, 65 into one or more of three totalizers 5, 6 and

7. The pin 15, which previously locked the wheel 16 against rotation, will be unset as it escapes from the star-wheel 19 by a cam 33, lying in the path of this previously set pin.

In order to release the pin-wheel 16 at the 70 actuation of the numeral keys from "1" to "9," each of the links 12 is provided with a head 34, which engages a plate 35, universal to all of the heads 34. This plate is forced 75 backwardly at the actuation of any one of the pin-setting linkages by its numeral key, so as to rock a link 36 against the tension of a spring 37. The link 36 has connected to its other end a link 38, which operates an escapement mechanism 39 for a shaft 40, on 80 which the locking star-wheel 19 is secured. This escapement mechanism is more fully described in the parent application, and also in my Patent No. 1,244,397, dated October 23, 1917. The operation is such, however, 85 that at each depression of any of the numeral keys from "1" to "9", the locking star-wheel 19 is permitted to turn a quarter of a revolution, so as to permit the escapement of the previously set pin 15, and thus permit a 90 rotation of the valuating or indexing wheel 16 until the just set pin 15 comes into engagement with the star-wheel 19 and brings the pin-wheel 16 to a halt.

This valuating or indexing movement is 95 transferred to the computing wheels of the totalizers 5, 6 and 7. To do this the pin-wheel shaft 32 is provided with a beveled gear 41, which meshes with a beveled gear 42 secured to a shaft 43. The shaft 43 is arranged to drive a vertical shaft 44 through the intermediary of a train of gearing which permits the shaft 44 to be disconnected from the shaft 43, so that any computing, driving action of the motor 21 may 100 not have its effect on the computing wheels of the totalizers 5, 6 and 7. In the parent case, this had a particular purpose in varying the driving ratio between the shaft 43 and the shaft 44, so as to effect multiplication and division. This train of gearing includes a gear 45; loose on the shaft 43 and meshing with a gear 46 secured to a shaft 47. The gear 46 drives a gear 48 secured to a shaft 49, on which a beveled gear 50 is 115 secured, which, in turn, meshes with and drives a beveled gear 51 secured to the vertical shaft 44. The gear 45 is loose on the shaft 43 and is connected thereto by means of a clutch 52, including an element 53 secured to the gear 45 and engageable by an interlocking clutch element 54, splined on the shaft 43. The clutch element 54 is normally held in mesh with the clutch element 53, by means of a spring 55. To disengage 120 the clutch element 54 from the clutch element 53, so as to interrupt the connection between the driving shaft 43 and the driven shaft 44, there is provided a key 56, located at the front of the machine and having a 130

key-stem 57, projecting past a disk 58 secured to the clutch element 54. The key-stem 57 is provided with a lug 59 which engages the disk 58, and, when the key 56 is operated, disconnects the clutch 54 against the tension of the spring 55.

The shaft 44 is arranged to carry the indexing or valuating movements of the pin-wheel 16 into the computing wheels 8 of the totalizers 5, 6 and 7. For this purpose, there is loosely mounted on the shaft 44 three sets of beveled gears, indicated specifically, in Fig. 3, by the numbers 60 to 65. The beveled gears are arranged in oppositely-facing pairs which mesh with beveled gears 66, 67 and 68 secured to master-wheel-shafts 69, 70 and 71, respectively. Each of the master-wheel-shafts is provided with a master wheel, indicated specifically, for the totalizers 5, 6 and 7, by the reference numerals 72, 73 and 74, respectively. The pairs of gears 60, 61; 62, 63; and 64, 65 are loosely mounted on the vertical shaft 44 and arranged to be connected in driven relation with the shaft 44 by means of clutches 75 splined on the shaft 44, one located between each of the pairs of oppositely-facing beveled gears. Each of the clutches 75 may be shifted from an intermediate, disconnected, neutral position upwardly or downwardly into clutching engagement with the upper or lower beveled gear of each pair, so as to secure the same in driven relation with the shaft 44. When shifted in one direction to connect one of the beveled gears with the shaft 44, the associated master wheel will be driven to add, and when shifted in the opposite direction to clutch the other beveled gear to the shaft 44, the associated master wheel will be driven to subtract.

The computing wheels 8 of the totalizers have associated with them tens-carrying trains of gearing for carrying "1" to the next higher computing wheel when any particular computing wheel completes a revolution. This tens-carrying mechanism is driven from the motor 21, and is controlled in its rotation and direction of rotation concomitantly with the control of the rotation and direction of rotation of each master wheel by the clutches 75. For this purpose, each of the totalizers 5, 6 and 7 is provided with a tens-carrying shaft carrying at its end a beveled gear 76. Each of the beveled gears 76 meshes with and may be driven by a pair of oppositely-facing gears 77, 78. The gears 77, 78 for each of the totalizers 5, 6 and 7 are loosely mounted on a vertical shaft 79, and are connected to the shaft 79, similarly to the gears 60 and 65, by means of clutches 80, one individual to each of the pairs of beveled gears 77, 78. The clutches 80 are splined on the shaft 79, and are shifted with the clutches 75 so as to give rotations of the tens-carrying mechanism corre-

sponding to the rotations of the master wheels. The clutches 75 and 80 for each of the totalizers 5, 6 and 7 are shifted concomitantly, for the purpose just mentioned, by means of levers 81, 82 and 83 for the totalizers 5, 6 and 7, respectively. The shaft 79 is driven from the motor 21 by means of a train of gearing including a beveled gear 84 secured to the shaft 79 and meshing with a beveled gear 85 secured to a horizontal shaft 86. The shaft 86 is connected in driven relation with the motor shaft 22 by a gear 87 secured to the shaft 86 meshing with an intermediate gear 88, which is driven by a gear 89 secured to the motor shaft 22.

The train of gearing from the motor shaft 22 to the shaft 79 is to one side of the train of gearing from the motor shaft 22 to the master wheels. Thus, the tens-carrying mechanism may be rotated independently of the particular valuating movements of the master wheels if they are connected by the clutches 80.

The master wheels 72, 73 and 74 are arranged to travel with the carriage 3, so as to come into register step by step with the computing wheels 8 of the associated totalizers. The master wheel 72 travels continuously from left to right with a continuous traveling movement of the carriage 3 from right to left. The master wheels 73 and 74 travel from left to right step by step, and then turn quickly several times for one continuous traveling movement of the carriage 3 from right to left. To effect this traveling movement of the master wheels with the traveling of the typewriter carriage 3, the typewriter carriage 3 is provided at the rear thereof with a rack 90, Fig. 5, meshing with and driving a gear 91 secured to a vertical shaft 92. The shaft 92 is provided with a gear 93 driving a gear 94 on a shaft 95, which is provided at its forward end with a gear 96 meshing with a rack 97 secured to a master-wheel carriage 98. The train of gearing from the typewriter carriage 3 to the master-wheel carriage 98 is such that when the typewriter carriage advances step by step in letter-feeding direction from right to left, the master-wheel carriage 98 will advance concomitantly step by step from left to right.

The master wheel 72 is connected to a sleeve 99 provided on the master-wheel carriage 98, so that it will travel with the carriage, and is slidably mounted on the master-wheel shaft 69, so that it can travel along the same. The engagement of the shaft 69 with the master wheel 72 is angular, so that, although the master wheel 72 travels along the master-wheel shaft 69, it will rotate with the latter. This enables the master wheel 72 to come into register one by one with each of the computing trains represented by the computing or dial wheel 8

showing at the sight-opening of the totalizer 5. The position of the master wheel 72 at any particular moment is indicated by a pointer 100 secured to the master-wheel carriage 98 and located in register with the master wheel 72. The master wheel 72 travels inside of the computing wheels, which are provided with internal gears, in a manner more particularly described in my above-mentioned application and patent. This position, however, is accurately determined at any time by the pointer 100.

To give a concomitant step-by-step movement to the master wheels 73 and 74, they are slidingly mounted on the gear shafts 70 and 71 and connected to be traversed by sleeves 101 and 102 forming part of a master-wheel carriage 103. This forces the master wheels 73 and 74 to move in unison. The master-wheel carriage 103 is traversed from the master-wheel carriage 98 by means of a shifter 104, which is intermittently connected to the master-wheel carriage 98. For this purpose, the master-wheel carriage 98 is provided with a bar 105 having a series of openings 106 located at intervals from each other. Pick-up stops 107 may be adjustably secured along the bar 105 by means of pins 108 secured to the stops 107 and extending into the openings 106 in the bar 105. The pick-up stops 107 are each provided with a lug 109, which is arranged to engage in a notch 110 formed between shoulders 111 and 112 provided on the shifter 104.

The pick-up stops 107 are adjusted along the bar 105 according to predetermined positions of the vertical columns of figures to be typewritten on the work-sheet carried by the typewriter carriage 3.

The usual starting position of the master-wheel carriage 103 for the short totalizers 6 and 7 is that shown in Fig. 1, with the master wheels 73 and 74 in register with the highest computing wheels of the totalizers 6 and 7. This position is determined by a spring barrel 113 connected to the master-wheel carriage 103 by a clutch connection 114. Each of the pick-up stops 107 engages successively in the notch 110, so as to connect the shifter 104, and thus the master-wheel carriage 103, in traveling relation with the master-wheel carriage 98, so that the master wheels 73 and 74 are advanced step by step, against the tension of the spring barrel 113, with the travel of the long-totalizer master-wheel carriage 98. The master-wheel carriage 103 travels for the length of the short totalizers 6 and 7, so as to have a concomitant computing action in the wheels of the short totalizers 6 and 7 with several sections or groups of computing wheels of the long totalizer 5.

When the master wheels 73 and 74 have computed in the units computing wheels of the totalizers 6 and 7, the carriage 103 is

disconnected from the long-totalizer master-wheel carriage 98 by withdrawing the shifter 104 from engagement with the particular pick-up stop 107 with which it happens to be connected. This is done by the disconnector 115 lying in the path of a cam 116 provided on the shifter 104. The disconnector 115 acts against the tension of a spring 117, which normally holds the shifter 104 in such position as to cause it to connect with the particular pick-up stop 107 with which it happens to be in register. Thus, the master wheels 73 and 74 are advanced step by step with the advancing movement of the master wheel 72, so as to compute in the totalizers 6 and 7 with a concomitant computation in the several sections of the long totalizer 5. The master wheels 73 and 74 return after computing in the units computing wheels, so as to be ready to compute in synchronism with the computing wheels of the next section of the long totalizer 5. This is repeated for each section of the long totalizer 5, until the end of the typewritten line and the last section of the totalizer 5 are reached.

To prevent over-return movement of the vibrating master-wheel carriage 103 with the continuous return movement of the master-wheel carriage 98 and the typewriter carriage 3, the pick-up stops 107, when they engage the shoulder 111, force a cam 118 on the shifter 104 into engagement with a disconnector 119, so as to depress the shifter 104 against the tension of the spring 117, and thus clear the shifter from the particular pick-up stop 107 in register therewith.

When the carriage 98 of the master-wheel 72 returns to the left with the movement of the typewriter carriage to the right for the purpose of beginning a new line of writing, a special lug 120 on the column stop bar impinges against a pin 121 secured upon the right-hand end of a rack 122. Said rack engages the upper side of a pinion 123, the lower side of which is engaged by a lower rack 125, and, therefore, moves to the right as said frame moves to the left. A spring 124 around the shaft of the pinion 123 normally moves the rack 125 to the left and the rack 122 to the right. The rack 125 has a shoulder or extension 126, which, when it is moved to the right, engages a pin 127 extending from the cam 118, and therefore moves to the right with said rack the shifter 104 and the horizontal master-wheels 73 and 74 through the full distance of their travel to the right, and until the sloping advancing edge 116 of the shifter 104 is engaged by the disconnector 115, which thereupon depresses said shifter and detaches the pin 127 thereon from the shoulder 126 on the rack, so that the shifter 104 returns to the left under the action of the spring barrel 113. On its return it is arrested by the projection 109 on

the first of the series of column stops engaging the notch 110 on said cam 118. When the carriage 98 re-commences its movement to the right the upper rack 122 follows its movement under the tension of the spring 124 until it reaches its normal position.

The object of the above arrangement is to permit a column of any width, from three to twelve figures, commenced at the first writing space of the typewriter, to be computed in either or both of the horizontal computing mechanisms along with other columns of the same or greater or less width which are computed in the long totalizer. Were this mechanism not provided that result could not be obtained, for, although it would be possible to write a column, say, of three figures wide, at the extreme left of the writing space, and to actuate the first group of three wheels of the horizontal computing mechanisms in correspondence with the writing of the figures of said column, yet said wheels so actuated would not be the proper wheels to be computed with other columns of greater width. For instance, hundreds, tens and units might be added, respectively, to hundreds of thousands, tens of thousands and thousands. By the above contrivance it is provided that, when a column of three figures or less is to be computed at the extreme left of the writing line, it is only the computing wheels on the extreme right of either one or both of the horizontal computing mechanisms that are actuated. If a column six figures wide is written, then the six wheels on the extreme right of either or both of the horizontal computing mechanisms are actuated and so on, thus assuring that in all cases the computing wheels of either or both of the horizontal computing mechanisms will correspond in denominational value to the several figures of the columns.

The numeral keys 1 may be disconnected from the valuating or indexing mechanism by disengaging the hooks 10 from the brackets 128 attached to the key-levers 9, Fig. 1, in the manner fully disclosed in my aforementioned Patent No. 1,244,397.

In addition to this mechanism, there is provided means to permit the type-bars to be entirely disconnected from the numeral keys, so that computing may be done without typewriting. For this purpose, brackets 128^a are provided on the key-levers 9, said brackets having eyes which may be engaged by hooks 10^a connected to the links 135 which operate type-bars 136. There is also provided a horizontal bar or rack 130 having at its ends slots whereby it is mounted on headed studs or screws secured to the base of the typewriter, said rack having a finger-piece 134, whereby it may be shifted endwise. This rack or bar has forwardly-extending

fingers, each of which may be forked or slotted at 129 to bestride the hook 10^a to shift the same laterally, or in a direction across the key-lever system. When the rack or bar 130 is pulled from the position at Fig. 12 to 70 the position at Fig. 13, (where it is detained by notch 132 and spring 131) the hooks 10^a are shifted out of engagement with the eyes in the brackets 128^a, so that the keys may be manipulated for computing 75 purposes without writing.

The device may be made to compute both vertically in several computing zones or major columns, and horizontally for cross and gross totals. The long totalizer 5 may be 80 divided into sections or groups which compose individual computing heads. The dividing is taken care of by the positioning of the typewriter carriage for the several computing zones or columns. The stops 107 are 85 preferably located along the bar 5 to pick up the cross and gross totalizers 6 and 7 at predetermined intervals to correspond with the grouping of the computing wheels of the long totalizer 5. The cross and gross totalizers 6 and 7 will add horizontally the lines 90 of numbers which are added vertically in the long totalizer 5.

Each of the totalizers 5, 6 and 7 is separately controlled by the levers 81, 82 and 83, so that various combinations of adding, subtracting and neutral of the three totalizers can be had. This provides interruption of the drive from the indexing or valuating mechanism at each totalizer, so that any or all of them can be silenced. In addition, the drive to the shaft 44, which is common to all of the totalizers, can be interrupted by shifting the gear 45 out of mesh with the gear 46. This will silence all of the totalizers. Thus, any one of the totalizers may add or subtract, or be silenced, and all of the totalizers may be silenced at a common point.

Variations may be resorted to within the scope of the invention, and portions of the improvements may be used without others.

Having thus described my invention, I claim:

1. The combination with a traveling typewriter carriage, of a long computing unit including two primary elements, to wit: a long series of computing wheels and a master wheel having a relative traveling movement so as to bring about a step-by-step registering of said master wheel with each of said computing wheels, a plurality of short computing units, each comprising two elements, including a short series of computing wheels and a master wheel, one of the elements in each of said short computing units traveling relatively to the other so as to bring about a step-by-step registering of said master wheels with said computing 125 units.

wheels, a carriage for connecting the two traveling elements of said short computing units, so as to cause them to travel in unison, means for traversing the traveling element 5 of said long computing unit from said typewriter carriage, so as to travel continuously with the travel of said typewriter carriage, and means for intermittently traversing the traveling elements of said short computing 10 units during a continuous traveling movement of said typewriter carriage, with provision for silencing one of said short computing units at will.

2. The combination with a typewriter carriage, of a long totalizer having a capacity 15 of several computing zones or major columns of said typewriter carriage, a master wheel for said long totalizer, driving connections to enable said typewriter carriage 20 to traverse said master wheel step by step with a continuous step-by-step movement of said typewriter carriage, a plurality of short totalizers, master wheels for said short totalizers, means for silencing either of said last- 25 mentioned master wheels at will, a carriage common to both master wheels of said short totalizers so as to traverse them in unison with each other, and means for traversing said master-wheel carriage from said typewriter carriage.

3. The combination with a typewriter carriage, of a long totalizer having an aggregate capacity of a plurality of computing 35 zones or columns as determined by said typewriter carriage, a master wheel for said long totalizer, a master-wheel carriage connected to traverse said master wheel from said typewriter carriage, a plurality of short totalizers, master wheels for said short totalizers, means for determining the activity 40 and direction of movement of one of said last-mentioned master wheels, a secondary master-wheel carriage connecting said master wheels for said short totalizers to move 45 as a unit, and an intermittent pick-up connection between said long totalizer and said secondary master-wheel carriage, whereby said short totalizer master wheels will have 50 an intermittent movement in unison with said long totalizer master wheel.

4. The combination with a series of cross-computing and vertically-computing devices, each including two primary elements, 55 to wit, a computing head and a master wheel, of a shaft for each of said master wheels, a drive-shaft common to all of said master-wheel shafts, numeral keys for controlling the extent of rotation of said common drive-shaft, a traveling carriage, means for intermittently connecting primary elements of said cross-computing devices to said carriage, so as to effect a concomitant 60 relative movement between said cross-computing heads and the master wheels, means

for connecting a primary element of said vertically computing device to said carriage, and means for silencing any of said master-wheel-shafts at will.

5. The combination with a plurality of 70 cross-computing and vertically-computing devices, each comprising two primary elements, to wit, a computing head and a master wheel, of a shaft for each of said master wheels, a drive-shaft common to all of said master-wheel shafts, a series of numeral keys for controlling the extent of rotation of said common drive-shaft, means individual to each of said master-wheel shafts to determine the direction of drive of said master-wheel 75 shafts individually by said common drive-shaft, whereby some of said master-wheel shafts can rotate in one direction and others simultaneously in the opposite direction, a traveling carriage, means for intermittently 80 connecting primary elements of said cross-computing devices to said carriage, so as to effect a concomitant relative movement between said cross-computing heads and the master wheels, and means for connecting a 85 primary element of said vertically-computing device to said carriage.

6. In a computing machine, the combination with a key-controlled drive shaft, of a main or vertical computing head, a series of 95 cross-computing heads, each of said computing heads having an individual master-wheel shaft, all of said master-wheel shafts connected to said drive-shaft, and means to enable said drive-shaft to turn certain of 100 said master-wheel shafts in either direction, and simultaneously turn certain of the remaining master-wheel shafts in the opposite direction.

7. In a computing machine, the combination of a main computing head for vertical computation, a series of cross-computing heads or totalizers, a master wheel for each totalizer, shafts to which said master wheels are splined, one of said shafts for each master wheel, a series of keys, means controlled by said keys for rotating said master-wheel shafts simultaneously, means to move the master wheels simultaneously along their shafts and automatically return the master 110 wheels of the cross totalizers repeatedly during each run of the carriage, and means to determine at will whether or not one of said cross-computing shafts shall rotate.

8. In combination, a typewriter carriage, 115 a vertical totalizer and master wheel therefor, the carriage connected to effect relative travel between the master wheel and the totalizer, a series of cross totalizers mounted in single tier, one below another, master 120 wheels for the cross totalizers, a second carriage to coöperate with the paper carriage and movable independently thereof and connected to effect relative travel between the cross totalizers and their master wheels, to 125 130

effect successive computations during each run of the typewriter carriage, and means for determining the direction of rotation of the master wheels of said cross-totalizers.

- 5 9. In combination, a typewriter carriage, a vertical totalizer and master wheel therefor, the carriage connected to effect relative travel between the master wheel and the totalizer, a series of cross totalizers mounted 10 in single tier, one below another, master wheels for the cross totalizers, a second carriage to coöperate with the paper carriage and movable independently thereof and connected to effect relative travel between the 15 cross totalizers and their master wheels, to effect successive computations during each run of the typewriter carriage, and means for determining the activity and direction of rotation of the master wheels of said cross- 20 totalizers.

10. The combination of a typewriter carriage, a series of vertical totalizers therefor, a master wheel to coöperate with said totalizers in succession, a series of cross totalizers, 25 master wheels for the cross totalizers, means to connect said cross-totalizer master wheels to said typewriter carriage to travel in the reverse direction from the latter, and to return said cross-totalizer master wheels repeatedly 30 during each run of the typewriter carriage, and means to enable one of said vertical totalizers and one of said cross-totalizers to rotate in the same direction while the other cross-totalizer rotates in the 35 reverse direction.

11. The combination with a typewriter carriage, of a series of vertical totalizers therefor, a master wheel to coöperate with said totalizers successively during the run of 40 the carriage, a set of cross totalizers, a master wheel for each cross totalizer, means for connecting said master wheels as a unit to the typewriter carriage to move step by step in the opposite direction from the latter, 45 means for automatically disconnecting said cross master wheels as a unit from said carriage, and returning the cross master wheels and reconnecting them to said carriage, and means to enable said vertical totalizer master 50 wheel to rotate any one of said vertical totalizers in one direction while one of said cross-totalizer master wheels rotates in the same direction, and while the other cross-totalizer master wheel rotates in the reverse direction.

- 55 12. The combination with a letter-feeding carriage, of a plurality of vertical totalizers, a master wheel for said totalizers, means to enable said carriage to effect relative traveling between said master wheels 60 and said totalizers, a plurality of cross totalizers, a master wheel individual to each of said cross totalizers, individual shafts for all of said master wheels, a common drive-shaft for all of said master-wheel shafts, 65 a series of numeral keys for controlling the

extent of rotation of said common drive-shaft in either direction, means for intermittently connecting said cross-computing master wheels to move with said carriage, and means for determining whether or not said common drive-shaft shall rotate a selected one of said individual cross-totalizer shafts. 70

13. The combination with a step-by-step-feeding carriage movable through a succession of computing zones, of a plurality of 75 cross-computing mechanisms, each including a traveling element, automatic mechanism effective intermittently for connecting said traveling elements simultaneously to said carriage to be advanced thereby, and releasing them to return independently thereof during a single run of said carriage, a main computing mechanism of a length to compute in several zones and including a traveling element connected to said step-by- 80 step feeding carriage to advance and return therewith, and means for determining the state of either cross-computing mechanism during the connection of its traveling element with the carriage in different comput- 85 ing zones. 90

14. The combination with a letter-feeding carriage, of a plurality of cross-computing mechanisms, each including a traveling element, a single carriage for said traveling 95 elements, a coupler to connect said single carriage and said letter-feeding carriage, means dependent upon the movements of said letter-feeding carriage for releasing and reconnecting said coupler during the 100 movement of the letter-feeding carriage, a main computing mechanism, including an element connected to said letter-feeding carriage to advance and return therewith, and means for determining the activity and di- 105 rection of rotation of the main computing mechanism and either cross-computing mechanism. 110

15. The combination with a letter-feeding carriage, of a main computing mechanism 115 having the capacity of a plurality of zones and including an element connected to said carriage to advance and return therewith, a plurality of cross-computing mechanisms, each including a traveling element, auto- 115 matic mechanism effective intermittently for connecting said traveling elements to said carriage to be advanced thereby, and releasing them to return independently thereof, and shiftable means for causing said computing mechanisms to perform either ad- 120 dition or subtraction.

16. The combination with a letter-feeding carriage, of a main computing mechanism having the capacity of a plurality of zones 125 and including an element connected to said carriage to advance and return therewith, a plurality of cross-computing mechanisms, each including a traveling element, auto- 130 matic mechanism effective intermittently

for connecting said traveling elements to said carriage to be advanced thereby, and releasing them to return independently thereof, and shiftable means for causing any of said computing mechanisms to perform either addition or subtraction regardless of the nature of the computation performed by either of the others.

17. The combination with a letter-feeding carriage, of a main computing mechanism having the capacity of a plurality of zones and including an element connected to said carriage to advance and return therewith, a plurality of cross-computing mechanisms, each including a traveling element, automatic mechanism effective intermittently for connecting said traveling elements to said carriage to be advanced thereby, and releasing them to return independently thereof, and shiftable means for setting said computing mechanisms to either addition, subtraction or neutral.

18. In a combined typewriting and computing machine, the combination with numeral keys and a letter-feeding carriage controlled thereby, of a main computing mechanism having the capacity of a plurality of zones, a plurality of cross-computing mechanisms, each computing mechanism comprising a set of computing wheels, denomination-selecting means controlled by said carriage for said main computing mechanism, denomination-selecting means for each of said cross-computing mechanisms whereby the latter are brought into use by said carriage repeatedly during a single run of the carriage, means for operating the cross-computing mechanisms simultaneously with the main computing mechanism in each zone, to extents determined by the keys, and means for determining the activity of either cross-computing mechanism in any zone.

19. In a combined typewriting and computing machine, the combination with numeral keys and a letter-feeding carriage controlled thereby, of a main computing mechanism having the capacity of a plurality of zones, a plurality of cross-computing mechanisms, each computing mechanism comprising a set of computing wheels, denomination-selecting means controlled by said carriage for said main computing mechanism, denomination-selecting means for each of said cross-computing mechanisms whereby the latter are brought into use by said carriage repeatedly during a single run of the carriage, means for operating the cross-computing mechanisms simultaneously with the main computing mechanism in each zone, to extents determined by the keys, and means for controlling the activity and direction of each computing mechanism independently of the others.

20. In a combined typewriting and computing machine, the combination with nu-

meral keys and a letter-feeding carriage controlled thereby, of a main computing mechanism having the capacity of a plurality of zones, a plurality of cross-computing mechanisms, each computing mechanism comprising a set of computing wheels, denomination-selecting means controlled by said carriage for said main computing mechanism, denomination-selecting means for each of said cross-computing mechanisms whereby the latter are brought into use by said carriage repeatedly during a single run of the carriage, means for operating the cross-computing mechanisms simultaneously with the main computing mechanism in each zone, to extents determined by the keys, manually shiftable means for controlling the direction of said main computing mechanism in any zone, and other manually operable means for controlling the direction of each cross-computing mechanism in any zone.

21. In a combined typewriting and computing mechanism, the combination with a letter-feeding carriage movable through a succession of computing zones, of a main totalizing mechanism having a capacity of a plurality of zones, means to determine the state of said main totalizing mechanism for any zone, said totalizing mechanism including an element connected to said carriage to be advanced thereby, a plurality of cross-totalizing mechanisms, and means to enable the cross-totalizing mechanisms to compute simultaneously the numbers carried into the main totalizing mechanism either additively or subtractively in the succession of computing zones during a single run of the letter-feeding carriage.

22. In a combined typewriting and computing mechanism, the combination with a letter-feeding carriage movable through a succession of computing zones, of a main totalizing mechanism having a capacity of a plurality of zones, and including an element connected to said carriage to be advanced thereby, a plurality of cross-totalizing mechanisms, means to enable the cross-totalizing mechanisms to compute simultaneously the numbers carried into the main totalizing mechanism in the succession of computing zones during the single run of the letter-feeding carriage, and means to control the activity of each of said totalizing mechanisms independently of the others.

23. In a combined typewriting and computing mechanism, the combination with a letter-feeding carriage movable through a succession of computing zones, of a main totalizing mechanism having a capacity of a plurality of zones, and including an element connected to said carriage to be advanced thereby, a plurality of cross totalizing mechanisms, means to enable the cross-totalizing mechanisms to compute simultaneously the numbers carried into the main totalizing

mechanism in the succession of computing zones during a single run of the letter-feeding carriage, and means to control the activity and direction of operation of each of 5 said totalizing mechanisms independently of the others.

24. In a computing machine, the combination with a series of registering mechanisms, of a series of parallel shafts having actuators thereon, there being one shaft and one actuator for each registering mechanism, numeral keys for determining different degrees of rotation of said shafts and thereby the particular registering mechanism actuated 10 thereby, and means for silencing one of said shafts at will.

25. In a computing machine, the combination with a series of registering mechanisms, of a series of parallel shafts having actuators 20 thereon, there being one shaft and one actuator for each registering mechanism, numeral keys for determining different degrees of rotation of said shafts and thereby the particular registering mechanism actuated 25 thereby, and means for silencing any shaft at will.

26. In a computing machine, the combination with a series of registering mechanisms, of a series of parallel shafts having actuators 30 thereon, there being one shaft and one actuator for each registering mechanism, numeral keys for determining different degrees of rotation of said shafts and thereby the particular registering mechanism actuated 35 thereby, and means for determining the direction of rotation of one of said shafts independently of the other shafts.

27. In a computing machine, the combination with a series of registering mechanisms, 40 of a series of parallel shafts having actuators thereon, there being one shaft and one actuator for each registering mechanism, numeral keys for determining different degrees of rotation of said shafts and thereby the particular registering mechanism actuated 45 thereby, and means for determining the direction of rotation of any shaft regardless of the direction of rotation of any other.

28. In a computing machine, the combination with a series of registering mechanisms, 50 of a series of parallel shafts having actuators thereon, there being one shaft and one actuator for each registering mechanism, numeral keys for determining different degrees 55 of rotation of said shafts and thereby the particular registering mechanism actuated thereby, and means for rotating two of said shafts in unison.

29. In a computing machine, the combination with a series of registering mechanisms, 60 of a series of parallel shafts having actuators thereon, there being one shaft and one actuator for each registering mechanism, numeral keys for determining different degrees 65 of rotation of said shafts and thereby the

particular registering mechanism actuated thereby, and means for rotating any two of said shafts in unison.

30. In a computing machine, the combination with a series of registering mechanisms, 70 of a series of parallel shafts having actuators thereon, there being one shaft and one actuator for each registering mechanism, numeral keys for determining different degrees of rotation of said shafts and thereby the 75 particular registering mechanism actuated thereby, and means for rotating two of said shafts in unison in either direction.

31. In a computing machine, the combination with a series of registering mechanisms, 80 of a series of parallel shafts having actuators thereon, there being one shaft and one actuator for each registering mechanism, numeral keys for determining different degrees of rotation of said shafts and thereby the 85 particular registering mechanism actuated thereby, and means for rotating any two of said shafts in unison in either direction.

32. In a computing machine, the combination with a typewriter carriage, of a frame, 90 a series of computing registers having fixed positions with reference to said frame, said frame moving step by step with the typewriter carriage in the same direction through the entire travel of the latter, actuating 95 means for said computing registers carried by said frame, individual computing mechanisms fixed relatively to said frame, individual parallel shafts for said last-mentioned computing mechanisms, and means 100 for connecting two of said shafts together for intermittent movement with said frame during the continuous movement of the carriage.

33. In a computing machine, the combination with printing mechanism and a traveling carriage for determining different positions in which numbers may be printed, of 105 registering mechanisms for accumulating the numbers printed, said registering mechanisms each including a plurality of computing wheels and a master member relatively 110 movable, and means for controlling the relative movement between the computing wheels and master members in all of said 115 registering mechanisms, to separately cross-foot items of different classes printed in selected columns, and to individually foot items printed in single columns.

34. In a computing machine, the combination with printing mechanism, of a plurality of registers for accumulating separate groups of individual items, a plurality of cross-footing registers, and means for selectively rendering different ones of said cross-footing registers effective to compute the numbers printed in columns variably positioned on the work-sheet, as said numbers are accumulated in any selected one of said individual registers. 125 130

35. In a combined typewriting and computing machine, the combination with computing mechanism and numeral types, of numeral keys, connections enabling said 5 numeral keys to control the actuation of said types to print and the amount of movement of said computing mechanism, and means, including a series of hooks between said types and numeral keys, for breaking the 10 connection between said numeral keys and said types while leaving said connections from said keys to said computing mechanism free to act.

36. In a combined typewriting and computing machine, the combination with computing mechanism and numeral types, of numeral key-levers, connections enabling said 15 numeral key-levers to control the actuation of said types to print and the amount of movement of said computing mechanism, and means, including a series of members carried by said levers, a series of hooks connected to said types for engaging said members and a slide common to all of said hooks 20 to move them out of engagement with said members, so as to break the connection between said key-levers and said types while leaving said connections from said key-levers to said computing mechanism free to act.

37. The combination, with a main totalizer mechanism comprising a series of computing units capable of accumulating independent totals, of a master actuator for successively operating each of the units of 35 said series and capable of being brought into coöperative relation therewith by intermittent relative movement between said main totalizer mechanism and said master actuator from one end of said series to the other, 40 a plurality of totalizers capable of acting as accessories to each of the units of said main totalizer mechanism, a master actuator for each of said accessory totalizers, said accessory totalizers and the master actuators 45 therefor having a relative movement of repeated reciprocation in contradistinction to and during the complete period of relative movement between the series of units of said main totalizer mechanism and the 50 master actuator therefor, and means whereby any or all of said accessory totalizers can act successively in unison with any of the units of said main totalizer mechanism and with each other.

38. The combination, with a main totalizer mechanism comprising a series of computing units capable of accumulating independent totals, of a master actuator common to all of said units and also exclusive thereto, so as to 55 be capable of operating each of said units in succession, a plurality of accessory totalizers adapted to have their effectiveness varied at will, a master actuator individual to each of said accessory totalizers and capable of 60 actuating solely its accordant totalizer, and

actuating means for driving said master actuators in unison corresponding amounts, and for advancing said master actuators in unison step by step, the master actuators individual to said accessory totalizers reciprocating a number of times during each complete succession of advance movements of the master actuator with respect to the units of said main totalizer mechanism, so as to be in constant operative relation with the 70 accessory totalizers while the master actuator of the series advanced from one unit to another.

39. The combination, with a main totalizer mechanism comprising a series of computing units capable of accumulating independent totals, of a master wheel common to all of said units, means for advancing said master wheel successively into coöperative relation with one after another of said 80 units, a pair of accessory totalizers, a master actuator for each of said accessory totalizers, pick-up connections between said master wheel for said series of computing units and the master actuators of the accessory 85 totalizers, so that said accessory totalizers may be operated in unison with any one of the units of said main totalizer mechanism, and means for causing one or both of said accessory totalizers to be effective or ineffective 90 at will.

40. In a combined typewriting and calculating machine, the combination with typewriting mechanism including number keys and a carriage controlled thereby, of a 100 totalizer mechanism comprising a set of computing units capable of independently accumulating totals of numbers typewritten in different columns, a cross-totalizer, a gross-totalizer, and mechanism controlled by said 105 number keys for operating said totalizers, said totalizer-operating mechanism being in part common to all of said totalizers and including variably settable silencing and reversing mechanism, thus constituting means, 110 dependent upon one setting of said silencing and reversing mechanism, and effective, upon operating said keys to typewrite numbers in selected ones of said columns, for causing said numbers to be entered severally in the 115 corresponding units of said column-totalizer mechanism and concomitantly accumulated in said cross-totalizer, said gross-totalizer being rendered ineffective during such operation, said operating mechanism also constituting means, dependent on a different setting of said silencing and reversing mechanism, and effective on operating said number keys to print a total from said cross-totalizer in any other selected column, for 120 concomitantly effecting computations of different character by said cross and gross-totalizers, so as to remove the total from said cross-totalizer and enter the same in said gross-totalizer, said column-totalizer 125 130

mechanism being rendered ineffective at the time.

41. The combination, with a totalizer mechanism comprising a set of computing units capable of independently accumulating a plurality of column-totals, and a single master-member for all of said units, of a cross-totalizer, a single master-member individual to said cross-totalizer, means to enable said cross-totalizer to add together concomitantly by means of said single master-member the several amounts that are carried into the individual column totalizer units, a gross-totalizer, a single master-member individual to said gross-totalizer, and means to enable the total to be removed from the cross-totalizer and concomitantly carried into the gross-totalizer, independently of the column-totalizer units.
- 20 42. In a combined typewriting and calculating machine, the combination with numeral typewriting keys and a carriage controlled thereby and movable to different computing zones, of a totalizer mechanism comprising a set of computing units capable of independently accumulating totals of numbers typewritten in different columns, a single master-wheel for operating said col-

umn-totalizer units successively under the control of said keys as the carriage moves to successive zones, a cross-totalizer, a single master-wheel therefor, means to enable said keys to operate said cross-totalizer master-wheel in every one of said zones concomitantly with the apposite column - totalizer unit, a gross-totalizer, and a master wheel individual thereto, said gross-totalizer being operable by said keys independently of the column-totalizer units, to accumulate the cross-total at the same time that the cross-totalizer is operable by the keys to remove the cross-total therefrom.

43. The combination with a typewriting mechanism having a traveling carriage with a movement determining the length of a written line, of a plurality of totalizers, controlling mechanism including a series of members, one for each totalizer for individually controlling the activity of the associated totalizers, and a single key for controlling the activity of all of said totalizers.
